UNITED STATES PATENT OFFICE.

WILLIAM A. RINGLER, OF PHILADELPHIA, PENNSYLVANIA.

LOOSE-LEAF LEDGER WITH VISUALIZED ARRANGEMENT OF ACCOUNT SHEETS.

Application filed April 28, 1924. Serial No. 709,552.

To all whom it may concern:

Be it known that I, WILLIAM A. RINGLER, a citizen of the United States, residing at Philadelphia, in the county of Philadelphia, 5 State of Pennsylvania, have invented a new and useful Loose-Leaf Ledger with Visualized Arrangement of Account Sheets, of which the following is a specification.

One of the main objects of my present invention is to devise a novel construction and arrangement of a loose leaf ledger wherein account sheets are employed which are removably carried by sheet holders.

With the above and other objects in view 15 which will hereinafter more clearly appear, my invention comprehends a novel construction and arrangement of a loose leaf ledger.

It further comprehends a novel construction and arrangement of sheet holders which 20 are provided with locking means to secure the account sheets in proper alignment, and, if desired, with the proper spacing between the sheets so that the title of each sheet will be visible.

25 It further comprehends a novel construction of account sheets.

Other novel features of construction and advantage will hereinafter more clearly appear in the detailed description and the appended claims.

30 For the purpose of illustrating the invention, I have shown in the accompanying drawing a typical embodiment of it, which, in practice, will give reliable and satisfactory results. It is however to be understood that this embodiment is typical only and that the various instrumentalities of which my invention consists can be variously arranged and organized, and that the invention 35 is not limited to the precise arrangement and organization of these instrumentalities as herein set forth.

Figure 1 represents a top plan view of a loose leaf ledger, with visualized arrangement of account sheets embodying my invention.

40 Figure 2 represents a section on line 2—2 of Figure 1.

Figure 3 represents a section on line 3—3 45 of Figure 1.

Figure 4 represents a top plan view of assembled account sheets.

Figure 5 represents a section on line 5—5 50 of Figure 4.

Figure 6 represents a fragmentary perspective of a sheet holder.

Figure 7 represents a plan view of an account sheet embodying my invention.

Figure 8 represents a plan view of an account sheet forming another embodiment of my invention.

Similar numerals of reference indicate corresponding parts.

Referring to the drawings:

1 designates a loose leaf ledger with account sheets and sheet holders embodying my invention. 2 designates a binder which may be of any desired or conventional construction, and, as such binders are well known in the art, I will describe the one illustrated in the drawings with only sufficient clearness to enable one to clearly understand the operation.

The binder consists of the binding members 3 and 4 which are relatively contractible and expandible, the binding member 3 being fixed to the post 5 and the binding member 4 being slideable thereon and provided with means to lock it in the position to which it has been adjusted.

The binding member 3 has hinged to it a leaf 6, and, in a similar manner, the binding member 4 has hinged to it the leaf 7 so that the ledger when assembled is in book form. 8 designates leaf or sheet holders which are formed of sheet material, such as card board or press board, and have their inner ends deflected around the filler members 9 as at 10, see Figure 6, from which it will be understood that, in the form illustrated, the inner ends of the sheet holders are folded around rectangular strips and secured thereto in any desired manner, for example, by adhesive.

Each sheet holder has secured to it, in any desired manner, a strip of material 11, extending transversely across it and provided with the weakened lines 12 and 13, thereby forming the folds 14 and 15, respectively. This strip 11 is preferably of relatively stiff material such as for example press board, and the fold 14 at its opposite ends is apertured as indicated at 16.

17 designates the account sheets which are usually made of paper and may be of any desired width. These sheets at their inner ends are provided with weakened lines 18 and 19 respectively, thereby forming a re-

taining flap 20. Between the weakened lines near opposite edges, I preferably provide spacing tongues 21 which are directed towards each other, and, if desired, only one 5 of the spacing tongues can be employed, as shown in Figure 8. If a spacing tongue is employed near each edge of the sheet, the sheet can be readily reversed and the same spacing will be provided as if the original 10 side of the sheet were being used. The account sheets are locked in position with respect to the sheet holder by means of locking members 22 which are preferably made of sheet metal, which is deflected to form 15 arms 23, which are secured to the sheet holders by means of any desired type of fastening device 24 which will permit movement of the locking member 22. As illustrated, this fastening device is shown as a rivet or 20 paper fastener. Each locking member 22 is deflected to form an upper plate 25 and a lower plate 26, thereby forming a slot 27, so that when the locking member 22 is moved inwardly into the position seen in 25 Figure 1, the account sheets will be in their locked position, as will be hereinafter more clearly explained.

One of the plates 25 or 26 has the material inwardly bulged as at 28 to form a 30 locking portion which is adapted to extend into the juxtaposed aperture 16 and thus prevent the accidental unlocking of a locking member 22.

The manner in which the parts are assembled will be readily understood by reference to Figures 2 to 6 inclusive. The spacing tongues 21 form spacing members so that when the account sheets are assembled 35 a portion of the card near one marginal edge will be visible as indicated at 29 in Figure 4. The flap 20 of each card is bent over and inserted beneath the fold 14, and the fold or flap 15 is then turned to lie beneath the fold 20, as will be understood by 40 reference to Figure 2. The locking members 22 are now moved into their locking position, and the account sheets will be firmly secured in their properly aligned position with respect to their sheet holders.

50 The inner portion of each sheet holder with the filler member 9 serves as a spacing device so that when the ledger is closed the leaves 6 and 7 will be disposed substantially parallel to each other.

55 It will of course be understood that the spacing members 21 can be dispensed with, if desired, and the operator can space the account sheets as may be desired so that the titles will be rendered visible, or they may 60 be secured in such relative positions that only the title of the uppermost sheet will be visible.

It will be understood from Figure 6 that the filler member 9 and the portion of the 65 sheet which surrounds them are apertured

as at 30 in order to permit the posts 5 to pass therethrough.

It will now be apparent that I have devised a new and useful loose ledger with visualized arrangement of account sheets, 70 which embodies the features of advantage enumerated as desirable in the statement of the invention and the above description, and while I have, in the present instance, shown and described a preferred embodiment there- 75 of which will give in practice satisfactory and reliable results, it is to be understood that this embodiment is susceptible of modification in various particulars without departing from the spirit or scope of the invention or sacrificing any of its advantages.

Having thus described my invention, what I claim as new and desire to secure by Letters Patent, is:

1. A sheet holder comprising a sheet of 85 material having on one side intermediate its ends a piece of material formed with a plurality of folds, and means to secure said folds in their folded position.

2. A sheet holder comprising a sheet of 90 material, a spacing member to which one end of said sheet is secured, a strip secured to said sheet and provided with a plurality of folds one of which is adapted to form a locking flap, and means to secure said folds 95 in their folded position.

3. A sheet holder comprising a sheet of material having extending outwardly from it intermediate opposite edges, a piece of 100 material formed with a plurality of folds one of which is adapted to form a locking flap, and a clip having a slot to adapt it to embrace the ends of the folds and the juxtaposed portion of the sheet.

4. An account sheet comprising a sheet 105 having a plurality of weakened lines near one end, one of said lines providing a foldable locking portion, and said sheet having between said lines a spacing tongue.

5. An account sheet for a visible ledger 110 comprising a plurality of sheets each having a foldable flap at one end and in proximity to said flap near one corner a spacing tongue whereby when said sheets are superimposed, a portion of the transverse edge of each 115 sheet is visible.

6. A plurality of account sheets comprising a plurality of sheets, each having at one end a foldable flap and having in proximity to said flap near one of its edges a projecting 120 tongue adapted to overhang the transverse edge of a superimposed sheet, the distance of said tongue from the juxtaposed edge of the sheet determining the visibility of the sheets when assembled.

7. An account sheet having weakened lines near one end, one of said lines forming a foldable locking portion, said sheet having near opposite marginal edges spacing 125 tongues singly adapted to engage the edge 130

of an adjacent sheet in normal or reversed position of the sheet thereby rendering a portion of the first sheet visible when assembled above a similar sheet.

- 5 8. An account sheet having at one end a filler member to which it is connected and having intermediate its ends a piece of material formed with a plurality of folds the outer of which forms a locking flap, in
10 combination with an account sheet having a foldable flap at one end beneath which said locking flap is folded, and means to retain said flap in its folded position.

9. A sheet holder having intermediate its
15 ends a piece of material formed with a plurality of folds extending across the sheet holder in combination with a plurality of account sheets each having at one end a foldable flap and a spacing tongue in proximity to such flap to overhang the transverse edge of another sheet and be positioned beneath said flaps when the latter are folded, one of said folds being adapted to be moved beneath said flap and above
20 said spacing tongues, and means to secure said folds in their folded position.

10. A loose leaf book sheet having a pair of parallel flaps arranged upon opposite faces, each flap being folded over upon itself and then upon a parallel line against a
30 face of the sheet, and a plurality of overlapping index sheets arranged edgewise along the folded flap on each face with a marginal portion of each index sheet projecting
35 beyond the margin of the superimposed index sheets for receiving identification symbols, the edges along the flap being folded within the flap and within both folds thereof so as to be anchored thereto.

- 40 11. A loose leaf book sheet having a pair of parallel flaps arranged upon opposite faces, each flap being folded over upon itself and then upon a parallel line against a face of the sheet, a plurality of overlapping index sheets arranged edgewise along the folded flap on each face with a marginal portion of each index sheet projecting beyond the margin of the superimposed index sheets for receiving identification symbols, the edges along the flap being folded within the flap and within both folds thereof so as to be anchored thereto, and means holding the flaps in folded relation against the book sheet and operable to release the flaps for unfolding in order to rearrange, add or remove any index sheets.

- 45 12. A loose leaf book sheet having a pair of parallel flaps arranged upon opposite faces, each flap being folded over upon itself and then upon a parallel line against a face of the sheet, a plurality of overlapping index sheets arranged edgewise along the folded flap on each face with a marginal portion of each index sheet projecting beyond the margin of the superimposed index

sheets for receiving identification symbols, the edges along the flap being folded within the flap and within both folds thereof so as to be anchored thereto, and clips hinged to the book sheet adjacent the ends of the flaps for movement into positions in which they lock the flaps folded and against the faces of the book sheet, or into positions releasing the flaps for unfolding when the index sheets are to be rearranged or changed.

50 13. A loose leaf book sheet having a pair of parallel flaps arranged upon opposite faces, each flap being folded over upon itself and then upon a parallel line against a face of the sheet, and a plurality of record sheets arranged edgewise along the folded flap on each face with the edges along the flaps folded therein and against the book sheet so as to be anchored thereto.

55 14. A loose leaf book sheet having a pair of parallel flaps arranged upon opposite faces, each flap being folded over upon itself and then upon a parallel line against a face of the sheet, a plurality of record sheets arranged edgewise along the folded flap on each face with the edges along the flaps folded therein and against the book sheet so as to be anchored thereto, and means for holding the flaps in folded relation against the book sheet and operable to release the flaps for unfolding when the record sheets are to be inserted or removed.

60 15. A loose leaf book sheet having a pair of parallel flaps arranged upon opposite faces, each flap being folded over upon itself and then upon a parallel line against a face of the sheet, a plurality of record sheets arranged edgewise along the folded flap on each face with the edges along the flaps folded therein and against the book sheet so as to be anchored thereto, and clips hinged to the book sheet adjacent the ends of the flaps for movement into positions in which they lock the flaps folded and against the faces of the book sheet, or into positions releasing the flaps for unfolding when the record sheets are to be rearranged or changed.

65 16. A binder for loose sheets comprising a base sheet having a free flap folded upon itself and then upon a parallel line of fold against a face of the base sheet, and means movably mounted on the base sheet for holding the flap in folded condition against the base sheet.

70 17. A binder for loose sheets comprising a base sheet part having a free flap part folded upon itself and then upon a parallel line of fold against a face of the base sheet part, and clips hinged to one of said parts for movement into and out of interlocking relation with the other part to hold the flap in folded condition against the base part.

75 18. A binder for loose sheets comprising a base sheet having a free flap folded upon

itself and then upon a parallel line of fold against a face of the base sheet, and a clip hinged to the base sheet for movement over the folded flap to confine it against the base sheet.

19. A binder for loose sheets comprising a base sheet having a free flap folded upon itself and then upon a parallel line of fold

against a face of the base sheet, a locking member having means to project over the flap and retain it in folded condition against the base sheet, and a plurality of record sheets folded along corresponding edges within both folds of the flap so as to be anchored thereto.

WILLIAM A. RINGLER.
